F. F. HENDRICKSON.
DRUM BEATER.
APPLICATION FILED NOV. 17, 1915.

1,186,189.

Patented June 6, 1916.

UNITED STATES PATENT OFFICE.

FRANK F. HENDRICKSON, OF GARFIELD, NEW JERSEY.

DRUM-BEATER.

1,186,189.

Specification of Letters Patent.

Patented June 6, 1916.

Application filed November 17, 1915. Serial No. 61,967.

To all whom it may concern:

Be it known that I, FRANK F. HENDRICKSON, a citizen of the United States, residing at Garfield, in the county of Bergen and State of New Jersey, have invented certain new and useful Improvements in Drum-Beaters, of which the following is a specification, reference being had to the accompanying drawings.

13 This invention relates to certain improvements in drum beaters and has relation more particularly to a device of this general character especially designed and adapted for use in connection with bass drums; and it is 15 an object of the invention to provide a device of this general character having novel and improved means whereby the same may be operated with convenience and facility through the medium of the pedal and where- 20 by the device may be readily and effectively clamped in operative position upon the drum.

The invention consists in the details of construction and in the combination and arrangement of the several parts of my improved drum beater whereby certain important advantages are attained and the device is rendered simpler, less expensive and otherwise more convenient and advantageous for 30 use, all as will be hereinafter more fully set forth.

The novel features of the invention will be carefully defined in the appended claim.

In order that my invention may be the 35 better understood, I will now proceed to describe the same with reference to the accompanying drawings, wherein—

Figure 1 is a view in side elevation illustrating a drum beater constructed in accordance with an embodiment of my invention, a coacting portion of a drum and cymbal being shown in section; Fig. 2 is a view in front elevation of my improved beater as herein embodied; Fig. 3 is a sectional view 45 taken substantially on the line 3—3 of Fig. 1; Fig. 4 is a fragmentary view illustrating a detail of my present invention relative to the striker arm; and Fig. 5 is an enlarged fragmentary sectional view illustrating the 50 mounting for the beater rod.

As disclosed in the accompanying drawings, R denotes the rim of a bass drum and C a conventional cymbal and 1 denotes a foot adapted to underlie the rim R and has 55 coacting therewith the clamping plate 2 which overlies the rim R and is operatively

engaged therewith through the medium of the winged nut 3 threaded upon the up- 60 standing member 4 carried by the foot 1. The plate 2 is removably mounted upon the foot 1 and is provided in its outer end with an open slot 5 to receive the headed member 6 in threaded engagement with the foot 1. It is also to be noted that the member 4 is 65 directed through an open slot 7 produced in the opposite end of the clamping member 2.

One side of the foot 1 at its forward end is offset, as at 8, and extending upwardly from said offset portion is the standard 9 of predetermined height and has its upper or 70 free extremity provided with an opening 10 through which is directed the stub shaft 11. The shaft 11 is maintained in applied position through the medium of the clamping members 12 and 14 threaded upon the shaft 75 11 and arranged at opposite sides of the standard 9. The shaft 11 is also disposed through an opening 15 formed in the rod supporting member 16, the opposite faces of said member 16 being provided with the 80 race-ways 17 concentric to the opening 15 and in which the anti-friction members 18 are arranged, said anti-friction members being preferably spherical bodies. The adjacent face of the clamping member 14 is 85 truncated in form and coacts with the anti-friction members 18 at one side of the member 16 while the anti-friction members 18 at the opposite side of the member 16 coact with the annular tapered face 19 of the head 90 20 formed on the outer end of the shaft 11. The head 20 is provided with the groove 21 to permit convenient removal or application of the shaft 11. The upper face of the member 16 at a point offset relative to the shaft 95 11 is provided with a recess or pocket 22 to receive the lower extremity of the beater rod 23, said rod being clamped to the member 16 through the medium of the clamping screw 24. The outer end of the beater rod 100 25 is provided with the beater 25 preferably formed of solid felt.

26 denotes a U-shape member straddling the rod 23 and having disposed through the arms thereof the clamping bolt 27 with 105 which coacts the winged nut 28 whereby the member 26 may be effectively secured at a predetermined point longitudinally of the rod 23. The bolt 27 also serves as a pivot for the striker arm 29 adapted to engage 110 the cymbal C, the outer end of the arm 29 being provided with the head 30 for direct

contact with the cymbal C. It is to be observed that downward movement of the striker arm 29 is limited by contact of the pivoted end thereof with the rod 23 but the 5 upper portion of the pivoted end of said striker arm 29 is rounded, as at 31, so that said striker arm may be readily thrown out of operative position when it is desired to have the head 25 coact with the drum without 10 out a sounding of the cymbal. The forward face of the offset portion 8 of the foot is provided with a recess 32 adapted to receive an end portion of the rod 33 of predetermined length, the outer end of said rod being 15 bent at right angles, as at 34, to intersect the plane occupied by the foot 1. Pivotally engaged with the angular portion 34 are the arms 35 arranged at the lower end of the pedal P, while the upper end of 20 said pedal is operatively connected through the medium of the interposed link 36 with the upstanding arm 37 preferably arranged at right angles to the rod 23, said arm 37 being carried by the member 16. The member 25 30 is also provided with a depending lip 38 to which is secured an extremity of a retractable member 39, herein disclosed as a coil spring, the opposite extremity of said member 39 being secured to the clip 40 capable of adjustment longitudinally of 35 the upright 9 whereby the tension of the retractable member 39 may be regulated in order to assure the requisite balance of the parts. As herein disclosed, the standard 9 is provided with a longitudinally disposed slot 41 through which is directed the headed screw member 42 also disposed through the clip 40 and said screw 42 has coacting therewith a winged clamping nut 43 where 40 by said clip is effectively maintained in its desired adjustment relative to the standard 9.

From the foregoing description, it is thought to be obvious that a drum beater 45 constructed in accordance with my invention is of an extremely simple and comparatively inexpensive nature and is particularly well adapted for use by reason of

the convenience and facility with which it may be assembled, and it will also be obvious that my invention is susceptible of some change and modification without material departure from the principles and spirit thereof and for this reason I do not wish to be understood as limiting myself to 55 the precise arrangement and formation of the several parts herein shown in carrying out my invention in practice.

I claim:

A drum beater consisting of a standard, 60 a shaft disposed through the upper end of the standard, clamping members mounted upon the shaft and coacting with the opposite faces of the standard, a holder member rotatably mounted upon the shaft adjacent 65 one of the clamping members, each opposite face of the holder being provided with a race-way, one of said race-ways coacting with the adjacent face of the clamping member, said shaft being provided with a 70 head coacting with the second race-way of the holder, anti-friction members arranged within each race-way, a beater rod engaged with the holder, a rod detachably engaged with the standard adjacent 75 the lower end thereof and having its outer end angularly disposed, a pedal rotatably supported by the angular portion of the rod, an arm carried by the holder member, a link interposed between the inner end of the 80 pedal and the outer end of the arm of the holder member; a clip secured to the standard below the holder member and capable of adjustment longitudinally of the standard, and a retractile member interposed between the clip and the holder for automatically imparting movement to the holder member in a direction opposite to the movement of the holder member afforded by a 85 depression of the pedal.

In testimony whereof I hereunto affix my signature in the presence of two witnesses.

FRANK F. HENDRICKSON.

Witnesses:

JOHN C. COFFEY,
JOHN J. MINOGAN.
